[57] CLAIM

The ornamental design for a pager holder, as shown and
described.

DESCRIPTION

FIG. 1 is a perspective view of a pager holder showing my
new design;

FIG. 2 is a rear view thereof;

FIG. 3 is a right side view thereof;

FIG. 4 is a left side view thereof;

FIG. 5 is a top plan view thereof; and,

FIG. 6 is a bottom plan view thereof.

The dotted lines in FIGS. 2, 4 and 6 show a pager inserted
into the holder.
